United States Patent Office.

J. W. LEWIS, OF OREGON CITY, OREGON.

Letters Patent No. 91,643, dated June 22, 1869.

IMPROVEMENT IN GANG-PLOWS.

The Schedule referred to in these Letters Patent and making part of the same.

To all whom it may concern:

Be it known that I, J. W. LEWIS, of Oregon City, in the county of Clackamas, and State of Oregon, have invented a new and useful Improvement in Gang-Plows; and I do hereby declare that the following is a full, clear, and exact description of the same, reference being had to the accompanying drawings, forming a part of this specification.

This invention consists in the novel construction of a gang-plow, whereby efficiency, durability, and cheapness are combined.

Figure 1, in the accompanying drawings, represents a longitudinal section of a gang-plow, constructed according to my invention; and

Figure 2, a plan view of the same.

Figure 3 represents a transverse sectional view of the axle, with one wheel attached, showing a device employed in effecting vertical adjustment of the axle; and

Figure 4 represents another view of fig. 3, taken at right angles thereto.

Similar letters of reference indicate corresponding parts in the several figures.

A is an axle, mounted upon two wheels, B B, and provided with a tongue, C, substantially as other gang-plows.

Erected over said axle A is the ordinary drivers' seat D.

Within the frame which supports this seat, is provided a vertical guide-way or slot, a, within which is arranged, to slide up and down, a connecting-bolt, b, which passes transversely and in a horizontal direction through the front ends of two beams, E E. Said beams are hung to and dragged behind the above-described currie, by means of the said connection of the bolt b with the slot or guideway a.

The beams E E are provided with plows, F F, and are connected to each other by any suitable means, so as to leave sufficient space between them for the proper separation of the plows.

The rear portion of the tongue C is divided or bi-pronged, and with sufficient space between said prongs for reception of a lever, G.

Said lever G is horizontally arranged, and pivoted between the prongs of the tongue, at a point, c, in front of the axle, and with its rear end in position for operating against or under a friction-roller, e, attached between the beams E E.

Said friction-roller e is located at a suitable distance behind the connecting-bolt b, for obtaining the most satisfactory results in raising the said beams and disengaging the plows from the ground, say, at a point, x, in the drawings.

The front portion of this lever G carries a friction-roller, g, and is, furthermore, divided or bi-pronged, for reception, behind the said friction-roller g, of a curved arm, f.

Said curved arm f is attached to the lower extrem-

ity of a vertically-arranged hand-lever, H, so as to act against the rear and upper sides of the said friction-roller g, by the backward movement of the said hand-lever, while a different but similarly-acting arm, f', also attached to the lower extremity of the same lever, comes in contact with the said friction-roller from the front, and passes under the same, so as to act against the front and under sides of the said roller by the forward movement of the lever, so that the forward and backward movements of said hand-lever will cause the oscillation of said lever, thereby raising and lowering the beams E, together with the plows F.

Assistance may be rendered the plows to enter the ground more readily, when desirable, by means of a friction-roller, e', which is suspended in a swinging frame, immediately below the roller e, and against which the lower side of the rear end of the lever G acts, by the forward movement of the hand-lever H.

The axle A is not supplied with rigidly-attached arms or spindles for the wheels, as is usually the case, but is supplied with adjustable arms or spindles, o o, whereby a means of vertical adjustment is given to the said axle, for the purpose of varying, when desirable, the depth of penetration of the plows.

Said vertical adjustment is effected by means of a vertical slider, m, secured upon the shoulder of the arm o, and fitted to slide between lips n, forming a suitable guideway upon the extremity of the axle A, so that the sliding of the parts will cause the raising or lowering of the said arm o, relatively to the axle A, or a similar movement of the said axle relatively to the arm, when said arm is being supported upon the wheel.

Said slider m is provided with a rectangular forward extension, p, together with an upwardly-curved forward extension, p'.

To the forward extremity of the said rectangular forward extension p, is pivoted, through its lower extremity, a vertical or nearly vertical hand-lever, r, so as thereby to allow the said hand-lever a forward and backward movement, while it is guided, at the same time, in said movements, by a lip, s, secured thereon, and fitting over the upwardly-curved formation p' of the said slider m.

The said hand-lever r is provided, at its lower extremity, with a rectangular rearward extension or arm, r'. Said arm r' is of a corresponding length with the rectangular forward extension p of the slider m, and is connected with the upper side of the extremity of the axle A, or to the upper part of the guideway n, by means of a hinged link, or short toggle-lever, q, so that the forward or backward movement of the hand-lever r will cause the raising or lowering of the axle.

The axle is retained at its different degrees of adjustment, which may be thus given to it, by means of a spring locking-lever, V, arranged on the outside of the hand-lever r, and lengthwise thereof.

Said locking-lever V is pivoted upon the said hand-

lever r , by a pin passing through it and through ears, u , upon the said hand-lever, near its central portion; and it is provided at its lower extremity with a rectangular inward projection or locking-pin, V' , which passes through an opening in the lip s , and into any one of a series of holes, i , near the edge of the curved extension p' of the slider m .

For raising or lowering the axle, and thereby varying the depth of penetration of the plows in the ground, the upper extremities of the two levers r and V , which are arranged side by side, are taken at the same time, and so grasped by the hand as to force the locking-lever V towards the hand-lever r , thereby unlocking the said hand-lever by the withdrawal of the locking-pin V' from the hole i , in which it may be locked, when, by a forward or backward movement of said hand-lever, the axle may be raised or lowered at pleasure. By relaxing the grasp, after said adjustment has been effected, the locking-lever V is forced outward by the action of a spring, z , forcing the locking-pin V' into any one of the holes i which may be opposite to it, thereby locking the hand-lever r , and retaining the axle at said adjustment.

The application of a device, similar to the one above described, is necessary at each end of the axle, and operated by both hands simultaneously, to insure a uniform adjustment of both extremities of the said axle.

k k are cutters, so secured to the flat side of the plows F F as to present a cutting-front to said plows, for the separating or cutting asunder of roots, or other impediments, which may lie in the line of their course, and are or may be screwed, or bolted, or otherwise secured to the plows, so as to be easily removed for any desirable purpose.

These cutters k k are provided with curvilinearly formed edges, for more readily cutting or separating said roots, or other obstacles; and also, with their upper extremities of a laterally-curved formation to

one side or the other, for the better turning or directing off of the accumulating dirt, sticks, or stubble, thereby lessening the tendency in the plows to choke or clog.

The backward movement of the lever H causes, by the action of the curved arm f upon the friction-roller g , the raising of the front ends of the beams E , as illustrated by those parts of fig. 1 represented in red outline.

Said raised condition of the front ends of the said beams places the plows in a position for cutting their way out of the ground, and a further backward movement of the said lever H will cause the points of the plows to be raised above the surface of the ground.

The position of the beams E , while in this condition, may be reversed by the pressing of the foot of the driver upon a horizontally and forwardly-projecting foot-lever, I , attached to the forward ends of the beams E . Said pressing of the foot upon the lever I causes the beams to turn upon the friction-roller e as a fulcrum, thereby directing the points of the plows downward, so as to be in position for entering the ground upon the forward movement of the said lever.

What I claim as my invention, and desire to have secured by Letters Patent, is—

1. The hoisting-lever G of a gang-plow, arranged for operation, in connection with the hand-lever H , for raising the plows, substantially as herein described.
2. The curved extremities or arms f f' , in combination with the hand-lever H , and hoisting-lever G , substantially as and for the purpose herein set forth.
3. The swinging frame, and roller e , in combination with the beams E , and lever G , substantially as and for the purpose herein set forth.

J. W. LEWIS.
